Application May 4, 1936, Serial No. 77,819

17 Claims. (Cl. 237—12.1)

This invention has for its general purpose to provide a novel heating and ventilating system for stationary engine plants, that utilizes the heat from an air cooled exhaust pipe and/or muffler system to supply heat to the engine room when needed, and which, if desired, may utilize the exhaust pipe and muffler cooling system as a means for removing warm air from the room.

In the present type of air cooled exhaust pipe and muffler installations for one or more engine units, for example in natural gas compressor plants or pumping stations, the engine exhaust pipe leads from the engine room to a muffler outside, and is jacketed by a conduit (which also usually and preferably jackets the muffler) through which air is circulated to cool the pipe and the combustion gases. In such systems the air flow may conveniently be induced by virtue of the high velocity discharge of gases at the muffler outlet. In such systems, and as broadly contemplated by the invention, the exhaust pipe and muffler cooling air may be taken either from the engine room or from the outside atmosphere. Systems of this latter type comprise the subject matter of Patent No. 1,966,620, issued to John S. Fluor, Jr., on July 17, 1934, for Muffler.

By the present invention we are able to adapt such systems to serve the combined purposes of cooling the exhaust gas conduits, and supplying warm air to the engine room for purposes of heating. And, as mentioned, the same system optionally may include provision for exhausting warm air from the room. Ordinarily, the engine rooms are of large size and involve considerable expense for heating in cold weather, since the heat radiated from the engines is then insufficient to keep the room warm. On the other hand, the radiated heat greatly increases the normal summer temperatures to the extent that it is highly desirable to keep a rapid flow of warm air from the room. Obviously, by being able to incorporate in the exhaust pipe and muffler cooling system, means for utilizing the ordinarily wasted exhaust gas heat for the purpose of heating the room when required, and, in the same system, means for cooling the room, we are able to effect substantial economies, as well as to combine in simple and inexpensive form, the equipment required to serve all the above mentioned purposes.

The present system has various features of control that enable it to operate in such manner as to conform with the desired temperature conditions to be maintained in the engine room. Normally, the system may operate to circulate air to the exhaust pipe and muffler, without af-

fecting the room temperature. When it becomes necessary to heat the room, the system may then be adjusted to discharge all or a portion of the warm air heated by contact with the exhaust pipe and muffler, into the room and, if desired, to simultaneously exhaust air from the room. Or, for the purpose of cooling the room atmosphere, the system may be adjusted so that the exhaust pipe and muffler cooling air stream acts to draw warm air from the room.

All the above mentioned features and objects of the invention, as well as its various details of construction and operation, will be more fully understood from the following description of certain typical and illustrative forms of the invention. Throughout the description, reference is had to the accompanying drawings, in which:

Fig. 1 is a side elevation, partly in section, illustrating a typical dual engine exhaust pipe and muffler cooling system embodying the invention;

Fig. 2 is a sectional view on line 2—2 of Fig. 1, showing the dual exhaust pipe and air conduit arrangement;

Fig. 3 is an end elevation as viewed from line 3—3 of Fig. 1;

Fig. 4 is a fragmentary enlarged section showing the air controlled valve at the outlet end of the muffler; and

Fig. 5 is a view similar to Fig. 1, illustrating a variational form of the invention.

In Fig. 1 of the drawings, we show an engine room 10 having side walls 11, ceiling 12 and floor 13, below which is a space 14 containing the foundations for the diagrammatically illustrated internal combustion engines 15 and 15^a, see Fig. 2. Each of the typically illustrated engines has two pairs of exhaust pipes 16 discharging into pipe 17 which connects with a main exhaust pipe 18 extending through the side wall 11 of the room at 19, and connecting at its outer end with a vertically positioned muffler 20. The muffler 20 is shown somewhat diagrammatically with the understanding that it may be of any suitable type and construction. The muffler is mounted within and annularly spaced from a vertically extending stack, generally indicated at 21, comprising a lower shell 22 of comparatively large diameter, an intermediate upwardly tapered portion 23, and a discharge pipe 24.

As best illustrated in Fig. 4, the combustion gases are discharged upwardly from the muffler outlet 25 into the throat formed by the tapered wall 23 of the stack, the gases creating, by reason of their high velocity flow, an upward draft inducing an upward flow of air within the annu-

lar passage 26 between the muffler and the stack shell 22. For reasons that will hereinafter appear, we provide at a suitable point in the air passage, preferably at the muffler outlet, an adjustable means whereby the air flow into the stack outlet pipe may be restricted, or entirely cut off. While any suitable form of adjustable damper or valve may be used, we have shown as typical, a vertically adjustable valve 27 mounted within the lower end of the stack outlet pipe 24, and movable downwardly to a seating position of engagement with a frusto-conical flange 28 on the upper end of the muffler outlet 25. The valve 27 comprises a cylindric portion 29 slidably fitted within the pipe 24, and carrying a pair of bolts 30 projecting outwardly through vertical guide slots 31 in the wall of the pipe. The valve is held in open positions by nuts 32 that are taken up against the outside of the pipe, and the bolts are extended, as shown, to provide handles for moving the valve. The lower end 33 of the valve is flared outwardly to correspond with the angularity of baffle 28 of the stack wall 23, so that in its closed position, see Fig. 1, the valve seats flatly upon flange 28, and in its wide open position, the flared portion 33 fits the stack wall 23.

Referring now to Figs. 1 and 2, the exhaust pipes 16, 17 and 18 are jacketed by a conduit, generally indicated at 34, through which air is drawn from the room interior along the surfaces of the exhaust pipes, and thence into the stack 21. Conduit 34 includes a pipe 35 placed concentrically about the exhaust pipe 18 and having an inlet end 35a connecting with a jacket 36, (the jacket being fitted over the inlet end of the pipe) and an outer end joined at 37 to shell 22 of the stack. The jacket 36 serves as a removable air conduit applied to those portions of the exhaust pipes close to the engine. As shown in Fig. 2, each jacket includes branches 36a made up of half-sections 37 and 38 bolted together along flanges 45, and placed about exhaust pipes 17, the upper ends of the branches 36a being closed about the exhaust pipes as indicated at 39. Jacket sections 37 and 38 are attached at 40 to the inlets 41 of a section 36b of the jacket placed about exhaust pipe 18, and composed of half-sections 42 and 43 bolted together along flanges 44.

Air is taken into the exhaust pipe surrounding conduit trough an inlet pipe 71 projected into the end of jacket 36 and extending upwardly through floor 13 of the room. Pipe 71 is closed at its upper end and is provided with suitable means whereby the draft of air into the pipe from the room may be regulated. As typical, the inlet pipe is shown to carry a rotatable air valve 70 having ports 70a movable into and out of registration with similarly arranged ports in the pipe.

During operation at normal atmospheric temperatures, and when there is no necessity for heating the engine room 10, valve 27 is kept open so that in each engine and muffler unit, the upward draft induced by the discharge of combustion gases from the muffler outlet 25, acts to draw air into the conduit through the inlet valve 70 and pipe 71, then through annular passages 38 and 47 between the exhaust pipe 18, and jacket 36 and conduit 35, respectively, and thence upwardly through the muffler surrounding passage 22 into the stack outlet pipe 24. In this manner, there is induced a rapid circulation of air along substantially the full lengths of the exhaust pipe and muffler, thereby cooling the parts and lowering substantially the temperature of the exhaust

gases. At the same time, the circulated air becomes heated, and it is one of our primary objects to utilize the ordinarily lost heat thus transferred to the air, for the purpose of heating the engine room.

The stack shells 22 are connected at points below the muffler outlets by a conduit 48, see Fig. 3, through which, when the system operates as a heating unit, air is drawn into a blower 49 of suitable type driven by motor 50. Air is discharged by the blower 49 through pipe 51 extending through wall 11 into the upper interior of the engine room 10. It will be understood that under normal conditions, with the exhaust pipe and muffler cooling air being discharged to the atmosphere from the stack, blower 49 is not in operation, and conduit 48 may be closed off from the stacks by any suitable means, as for example blind flanges (not shown) inserted between the flanges of the joints at 52. It may be mentioned at this point that while we have shown as a typical embodiment of the invention, a system involving a dual arrangement of engines, exhaust pipes and mufflers, together with the air cooling jackets and stacks, the invention is in no way limited to this dual arrangement and may be adapted equally well to a single unit system.

Assuming now that it is desired to heat the engine room, the valve 27 is dropped to closed position as shown in Fig. 1, and the blower 49 is started into operation to draw the heated air from the muffler surrounding passages 22 through conduit 48, and to discharge the air through pipe 51 into room 10.

Both the temperature and quantity of the warm air being forced into the room may be controlled in any suitable manner. For example, rotatable sleeve valves 53, see Fig. 3, on conduit 48 may be adjusted to cool the air stream being discharged into the room, by permitting the blower to draw into the conduit through the valve controlled openings 54, the proportion of atmospheric air necessary to keep down the temperature of the air delivered to the room. Also we may regulate the quantity of air being discharged into the room by a suitable damper or other control, for example by means of a hollow slide damper 55 placed within the outlet end of pipe 51 and having ports 56 and 57 movable into and out of registration with the pipe openings 58 and 59, respectively. Damper 55 may be moved to the left to increase the flow of air through ports 56 and 58 into the room, and to the right to close off the entry of the heated air, the surplus of the blower discharge being exhausted to the atmosphere through ports 57 and 59. If desired, we may connect into pipe 51, a suitable air washing or filtering unit, diagrammatically indicated at F, for conditioning the air being passed into the room.

In the operation of the invention as explained in the foregoing description, the exhaust pipe and muffler cooling air initially is taken from the engine room and may either be discharged to the atmosphere, or returned to the room for heating purposes. In Fig. 5 we show a variational form of the invention similar in its details to the previously described embodiment, except that it provides a system for initially taking air from the atmosphere outside the room and circulating it, either with or without additional air being drawn from the room, in the manner previously described. In the variational form, the open end of conduit 35' terminates beyond the inlet end of exhaust pipe 18 to pro-

vide an air inlet at 61 into which air is drawn from an outer pipe 62 spaced about conduit 35' and extending through the room wall 11 to the outside. For the purpose of enabling inside as well as outside air to be taken into pipe 62, if desired, its inlet end 62a is extended beyond the inlet end of conduit 35', and is provided with suitable means, such as a damper 63, whereby an adjustable proportion of room air may be admitted.

In operation, assuming damper 63 to be closed, all the cooling air is drawn from the atmosphere outside the room through passage 66 between pipe 62 and conduit 35' into the open end 61 of the conduit, and thence through passage 67 into the muffler stack. As before, the air heated by contact with the exhaust pipe and muffler either may be discharged to the atmosphere, or it may be returned to the room through pipe 51 for heating the room. The system illustrated in Fig. 5 has an advantage in that fresh air from the outside atmosphere is taken in to heat the room. By opening damper 63, the system may operate simultaneously to remove air from the room and to maintain a downward circulation of warm air from pipe 51 to the exhaust pipe air conduit.

The invention also contemplates adapting either of the described systems for operation in a manner such that the blower acts to force cooling air along the muffler and exhaust pipe toward the engine, and thence into the room or to the outside atmosphere, instead of the air flow being induced in the opposite direction by the blower suction or muffler discharge according to the previously described methods. Thus, referring to Fig. 1, under some circumstances it may be desired to reverse the blower 48 (with valve 27 closed) so as to cause air to be drawn through pipe 51 either from the room interior or outside atmosphere, depending upon the adjustment of the damper 55, and to be discharged by the blower along the muffler and exhaust pipe in a direction countercurrent to the exhaust gas flow. The warm air finally is discharged from the exhaust pipe conduit through pipe 11 and the air valve 70 into the room atmosphere.

Assuming the system shown in Fig. 5 to be operated with the blower reversed, air taken in through pipe 51 is forced along the muffler and exhaust pipe to the outlet end 61 of conduit 35', and thence is discharged through passage 66 to the atmosphere outside the room. Provision is made whereby a portion only, or if desired, substantially all the heated air, may be discharged into the room, by installing an adjustable damper 63 within the open end 62a of the outer pipe 62. As will be apparent, the system is capable of operating to take air either from the upper interior of the room or the atmosphere outside, and to discharge the air after it becomes heated by contact with the muffler and exhaust pipe, to either or both the room interior or outside atmosphere.

65 We claim:

1. In a stationary engine plant the combination comprising an exhaust pipe extending from the interior to the exterior of a room and connected to an engine therein, a muffler connected to said exhaust pipe outside the room and discharging the combustion gases to the atmosphere, an air conduit surrounding and spaced from said exhaust pipe and muffler and forming an air passage having an inlet within said room, means for drawing air through said conduit from

the interior of the room and discharging the air to the outside atmosphere by the velocity effect of the combustion gases discharged from the muffler, and an annular valve within said passage, said valve being adjustable from the outside of said conduit to restrict the flow of air being drawn from the room. 5

2. In a stationary engine plant the combination comprising an exhaust pipe extending from the interior to the exterior of a room and connected to an engine therein, a muffler connected to said exhaust pipe outside the room and discharging the combustion gases to the atmosphere, an air conduit surrounding and spaced from said exhaust pipe and muffler and having an open inlet end within said room, means for drawing air through said conduit from the interior of the room and discharging the air to the outside atmosphere by the velocity effect of the combustion gases discharged from the muffler, and an annular valve at the gas discharge end of said muffler, said valve being adjustable from the outside of said conduit to restrict the flow of air thus being drawn from the room. 10

3. In a stationary engine plant the combination comprising an exhaust pipe extending from the interior to the exterior of a room and connected to an engine therein, a muffler connected to said exhaust pipe outside the room and discharging the combustion gases to the atmosphere, 20 an air conduit surrounding and spaced from said exhaust pipe and muffler and having an open inlet end within said room, means for heating air by passing it through said conduit in heat transferring relation with the exhaust pipe, and means 25 for discharging the heated air into the atmosphere of said room from that portion of said conduit surrounding the muffler. 35

4. In a stationary engine plant the combination comprising an exhaust pipe extending from the interior to the exterior of a room and connected to an engine therein, a muffler connected to said exhaust pipe outside the room and discharging the combustion gases to the atmosphere, an air conduit surrounding and spaced from said exhaust pipe and muffler and forming an air passage having an inlet within said room, means for heating air by passing it through said conduit in heat transferring relation with said exhaust pipe and muffler, a pipe extending into said room and connecting with that portion of said conduit surrounding the muffler, and a blower for discharging the heated air from said conduit through said pipe into the room. 40

5. In a stationary engine plant the combination comprising an exhaust pipe extending from the interior to the exterior of a room and connected to an engine therein, a muffler connected to said exhaust pipe outside the room and discharging the combustion gases to the atmosphere, 60 an air conduit surrounding and spaced from said exhaust pipe and muffler and forming an air passage having an inlet within said room, means for heating air by passing it through said conduit in heat transferring relation with said exhaust pipe and muffler, a pipe extending into said room and connecting with that portion of said conduit surrounding the muffler, a blower for discharging the heated air from said conduit through said pipe into the room, and means for selectively passing the heated air from the conduit to said blower or to the atmosphere outside said room. 65

6. In a stationary engine plant the combination comprising an exhaust pipe extending from

the interior to the exterior of a room and connected to an engine therein, a muffler connected to said exhaust pipe outside the room and discharging the combustion gases to the atmosphere, an air conduit surrounding and spaced from said exhaust pipe and muffler and forming an air passage, means for heating air by taking air from the atmosphere outside said room and passing it through a portion of said conduit within the room and in heat transferring relation with said exhaust pipe and muffler, a pipe connecting with said conduit at the muffler and extending into said room, a blower for discharging the heated air from said conduit through said pipe into the room, and means for selectively passing the heated air from the conduit to said blower or to the atmosphere outside said room.

7. In a stationary engine plant the combination comprising an exhaust pipe extending from the interior to the exterior of a room and connected to an engine therein, a muffler connected to said exhaust pipe outside the room and discharging the combustion gases to the atmosphere, an air conduit surrounding and spaced from said exhaust pipe and muffler and having an outlet end extending beyond the discharge end of the muffler, air being drawn through said conduit and discharged to the atmosphere by the velocity effect of combustion gases being discharged from said end of the muffler, and a valve positioned between the conduit and said discharge end of the muffler, said valve being adjustable to vary or close off the passage of air from the space surrounding said muffler to said outlet end of the conduit.

8. In a stationary engine plant, the combination comprising an exhaust pipe extending from the interior to the exterior of a room and connected to an engine therein, a conduit through which air is passed in heat transferring relation with the exhaust pipe, means for inducing air flow through said conduit into the combustion gas stream by virtue of the velocity of the gas stream, a motor driven blower connected to said conduit, a blower outlet conduit discharging into said room, and valve means for selectively passing heated air from said conduit to the first mentioned means or to said blower.

9. In a stationary engine plant, the combination comprising an exhaust pipe extending from the interior to the exterior of a room and connected to an engine therein, a conduit through which air is passed in heat transferring relation with the exhaust pipe, means for inducing air flow through said conduit into the combustion gas stream by virtue of the velocity of the gas stream, a motor driven blower connected to said conduit, a blower outlet conduit discharging into said room, valve means for selectively passing heated air from said conduit to the first mentioned means or to said blower, and an air washer in said blower outlet conduit.

10. In a stationary engine plant, the combination comprising an exhaust pipe extending from the interior to the exterior of a room and connected to an engine therein, means for conducting air along and in heat transferring relation with a substantial length of said exhaust pipe, said means comprising a jacket surrounding and spaced from the comparatively hot portion of the exhaust pipe extending toward the engine, means for inducing air flow through said jacket by the velocity of exhaust gases discharged through said exhaust pipe, and means independent of the last mentioned means selectively oper-

able for discharging heated air from said jacket into the atmosphere of said room.

11. In a stationary engine plant, the combination comprising an exhaust pipe extending from the interior to the exterior of a room and connected to an engine therein, means for taking air from the interior of said room and conducting the air along and in heat transferring relation with a substantial length of said exhaust pipe, said means comprising a jacket surrounding and spaced from the comparatively hot portion of the exhaust pipe extending toward the engine, means for inducing air flow through said jacket by the velocity of exhaust gases discharged through said exhaust pipe, and means independent of the last mentioned means selectively operable for discharging heated air from said jacket into the atmosphere of said room.

12. In a stationary engine plant, the combination comprising an exhaust pipe extending from the interior to the exterior of a room and connected to an engine therein, means for taking air from the atmosphere outside said room and conducting the air along and in heat transferring relation with a substantial length of said exhaust pipe, said means comprising a jacket surrounding and spaced from the comparatively hot portion of the exhaust pipe extending toward the engine, means for inducing air flow through said jacket by the velocity of exhaust gases discharged through said exhaust pipe, and means independent of the last mentioned means selectively operable for discharging heated air from said jacket into the atmosphere of said room.

13. In a stationary engine plant, the combination comprising an exhaust pipe extending from the interior to the exterior of a room and connected to an engine therein, means for conducting air along and in heat transferring relation with a substantial length of said exhaust pipe, said means comprising a jacket surrounding and spaced from the comparatively hot portion of the exhaust pipe extending toward the engine, means for inducing air flow through said jacket by the velocity of exhaust gases discharged through said exhaust pipe, independent means selectively operable to pass air through said jacket, and means for selectively discharging heated air passed through the jacket by the last mentioned means either to the atmosphere outside said room or into the room atmosphere.

14. In a stationary engine plant, the combination comprising an exhaust pipe extending from the interior to the exterior of a room and connected to an engine therein, means for taking air from the interior of said room and conducting the air along and in heat transferring relation with a substantial length of said exhaust pipe, said means comprising a jacket surrounding and spaced from the comparatively hot portion of the exhaust pipe extending toward the engine, means for inducing air flow through said jacket by the velocity of exhaust gases discharged through said exhaust pipe, independent means selectively operable to pass air through said jacket, and means for selectively discharging heated air passed through the jacket by the last mentioned means either to the atmosphere outside said room or into the room atmosphere.

15. In a stationary engine plant, the combination comprising an exhaust pipe extending from the interior to the exterior of a room and connected to an engine therein, means for taking air from the atmosphere outside said room and conducting the air along and in heat trans-

ferring relation with a substantial length of said exhaust pipe, said means comprising a jacket surrounding and spaced from the comparatively hot portion of the exhaust pipe extending toward the engine, means for inducing air flow through said jacket by the velocity of exhaust gases discharged through said exhaust pipe, independent means selectively operable to pass air through said jacket, and means for selectively discharging heated air passed through the jacket by the last mentioned means either to the atmosphere outside said room or into the room atmosphere.

16. In a stationary engine plant, the combination comprising an exhaust pipe extending from the interior to the exterior of a room and connected to an engine therein, a muffler connected to the exhaust pipe outside said room, a conduit surrounding said exhaust pipe and muffler and forming a passage communicable with the muffler outlet and through which air is conducted in heat transferring relation with the exhaust pipe, means for inducing air flow through said conduit by the velocity of exhaust gases discharged from the muffler, and selectively oper-

able means independent of the last mentioned means for discharging the heated air from said conduit into the atmosphere of said room.

17. In a stationary engine plant, the combination comprising an exhaust pipe extending from the interior to the exterior of a room and connected to an engine therein, a muffler connected to the exhaust pipe outside said room, a conduit surrounding said exhaust pipe and muffler and forming a passage communicable with the muffler outlet and through which air is conducted in heat transferring relation with the exhaust pipe, means for inducing air flow through said conduit by the velocity of exhaust gases discharged from the muffler, and selectively operable means independent of the last mentioned means for discharging the heated air from said conduit into the atmosphere of said room, the last mentioned means including a motor driven blower discharging the heated air from a point at the outside of the room into the interior thereof.
